GOLF BALL WASHER

Joseph John Goller, Amsterdam, N. Y.

Application June 9, 1950, Serial No. 167,060

3 Claims. (Cl. 15—21)

1

My invention relates to improvements in golf ball washers.

A primary object of the invention is to provide a golf ball washer including a pair of opposed scrubbing elements and means to resiliently urge the scrubbing elements together in contact with the ball being washed.

A further object is to provide a golf ball washer of the above mentioned character including a novel and simplified means for adjusting the tension on the opposed scrubbing elements, without the necessity of removing any part of the washing device from the receptacle or pail carrying it.

A further object is to provide a golf ball washer of the above mentioned character wherein wear on the cleaning or scrubbing elements is compensated for automatically.

A still further object is to provide an improved golf ball washer which is highly simplified, compact, sturdy and durable in construction and inexpensive to manufacture.

Other objects and advantages of the invention will be apparent during the course of the following description.

In the accompanying drawings, forming a part of this application, and in which like numerals are employed to designate like parts throughout the same,

Figure 1 is a side elevational view of a golf ball washer embodying my invention,

Figure 2 is a plan view of the same,

Figure 3 is a vertical sectional view taken on the line 3—3 of Figure 2,

Figure 4 is a vertical sectional view taken on line 4—4 of Figure 2, and,

Figure 5 is a fragmentary horizontal sectional view taken on line 5—5 of Figure 3.

In the drawings, where for the purpose of illustration is shown a preferred embodiment of my invention, the numeral 10 designates an upstanding vertical post or standard having a horizontal platform or tray 11 rigidly secured to its top end for receiving an upstanding open top receptacle or pail 12 constituting the body or casting of my golf ball washer.

The pail 12 is removably mounted upon the tray or platform 11, and provided in its flat bottom 13 with a removable drain plug 14, as shown. The pail may include a side wall which is slightly conically tapered or flared upwardly, and the pail is provided near its open top and at diametrically opposite points with a ring or towel holder 15 and golf club support clip or holder 16, both rigidly secured to the pail. Near and below the top of the pail, the same is provided with three cir-

5 cumferentially equidistantly spaced radially inwardly projecting apertured lugs or ears 17, rigidly secured to the side wall of the pail and arranged at the same elevation to form a seat for a horizontal flat circular support plate 18, rigidly secured thereto by three screws 19 or the like.

10 All of the operating parts of my golf ball washer are bodily carried by the support plate 18, so that all parts may be removed from the pail 12 as a unit, by simply removing the screws 19 and lifting the support plate 18. Rigidly secured to the bottom of the support plate 18 and suspended therefrom is a depending vertical U-shaped bracket or brush holder 20, including a flat horizontal bottom 21 spaced above the bottom 13 and opposed parallel vertical sides 22 which extend throughout substantially the entire height of the pail. Integrally secured to the top end of the sides 22 are flat horizontal laterally outwardly projecting mounting flanges 23, rigidly secured to the mounting plate 18 by screws 24 or the like.

15 Mounted between the sides 22 of the U-shaped brush holder 20 is a pair of opposed laterally spaced vertical brushes 25 and 26 which have their bristles 27 directed inwardly to form opposed spaced parallel substantially continuous scrubbing surfaces. The top ends of the brushes 25 and 26 are spaced a slight distance below the support plate 18, Figure 4, and the substantially flat scrubbing faces of the brushes extend perpendicular to the sides 22. The lower ends of the brushes are pivotally secured to the sides 22 by means of pairs of screws 28 or the like 20 which engage in the wooden backs of the brushes and are journaled in openings formed in the sides 22 of the brush holder. The arrangement is such that the upper ends of the brushes are freely swingable vertically toward and away from each other within the U-shaped brush holder 20.

20 A pair of diametrically oppositely disposed downwardly curved leaf springs 29 are secured to the bottom of the support plate 18 by pairs of rivets 30 or the like. These leaf springs 29 engage the backs of the brushes 25 and 26 near their tops to resiliently urge the brushes inwardly or toward each other. Adjusting screws 31 engage in screw threaded openings in the support plate 18 and contact the leaf springs 29, so that the tension of these springs against the brushes may be adjusted as desired. In this respect, it should be noted that it is unnecessary to remove any part of the washing mechanism from the pail 12 when adjusting the tension of the springs 29, the screws 31 being readily accessible from above the pail.

A flat vertical golf ball carrying member or paddle 32 is slidably mounted between the bristles 27 of the brushes for reciprocation, and this paddle 32 extends throughout the entire height of the brush holder 20 and operates through a water filling and golf ball admitting opening 33 formed in the support plate 18 and having diametrically oppositely disposed guide notches 34 for slidably receiving and guiding the paddle 32 which is equipped at its top end with an up-standing handle extension 35, as shown. The paddle 32 is provided near its bottom end with a diagonal slot or opening 36 forming a pocket for a golf ball to be scrubbed between the bristles of the brushes 25 and 26. The paddle 32 is further provided at its bottom end with pairs of horizontal transverse stop pins 37, which engage the bottom of the support plate 18 when the paddle is pulled upwardly, to prevent the paddle from passing completely through the opening 33 and being disconnected from the washer. As shown in Figures 2 and 3, the pairs of stop pins 37 are spaced apart sufficiently so that they straddle the bristles 27 of the brushes during the upward and downward movement of the paddle 32.

A foraminous soap cage or receptacle 38 of wire or the like is dependingly secured to the support plate 18 at a point near the side wall of the pail 12 and spaced from the brush holder 20, as shown. The cage 38 is adapted to contain a cake of soap to facilitate thoroughly cleaning and polishing the golf ball while it is being reciprocated between the brushes. When the water in the pail is agitated by the reciprocation of the paddle 32, there is a further tendency for the soap in the cage 38 to mix through the water.

Separate means are provided for rinsing or washing a golf ball without subjecting it to any brushing or scrubbing action. Such means comprises a depending vertical U-shaped bracket 39 having top horizontal apertured extensions or ears 40, rigidly secured to the support plate 18 by rivets 41 or the like. The bracket 39 further includes spaced parallel vertical sides or guide rails 42, and a transverse horizontal bottom end 43 arranged at the elevation of the bottom 21 and rigidly secured thereto by a transverse strap or plate 44, welded or otherwise rigidly secured to the end 43 and bottom 21. The plate 44 constitutes a brace for holding the bottom ends of the brackets 20 and 39 against lateral or side-wise movement. A ball holding disc or seat 45 is disposed between the guide rails 42 and provided at diametrically opposite points with notches 46, slidably receiving the guide rails therein to hold the disc 45 against turning. The disc 45 is downwardly dished or spherically recessed as at 47 to facilitate holding a golf ball. The disc 45 is carried by the bottom ends of a pair of spaced parallel vertical rods 48 which extend for the entire length of the bracket 39 and above the top of the support plate 18 as shown. The rods 48 have their upper ends integrally connected by a transverse horizontal bight portion or handle 49, and the rods 48 reciprocate through guide openings 50 formed in the support plate 18 at points radially outwardly of a large circular opening 51, also formed in the plate 18 to facilitate introducing and removing the golf ball from the disc 45. As shown in the drawings, the rods 48 are spaced ninety degrees from the guide rails 42 and form therewith a cage for holding the golf ball upon the disc 45. When the disc 45 is elevated into con-

tact with the bottom of the support plate 18, the golf ball will project above the opening 51 so that it may be removed from between the rods 48.

When it is desired to scrub a golf ball between the brushes 25 and 26, the paddle 32 is raised until the stop pins 37 contact the support plate 18. The opening or pocket 36 will then be arranged above the support plate 18 so that the golf ball may be introduced into it. The opening 33 is sufficiently large to accommodate the golf ball, when the paddle is lowered between the bristles 27 for scrubbing the ball. Likewise, when the scrubbing or cleaning operation is completed the golf ball is removed through the opening 33 after the paddle 32 is again elevated until the stop pins 37 contact the support plate 18.

As best shown in Figure 4, the top of the pail 12 extends a slight distance above the support plate 18 so that rain water falling on the plate 18 may pass into the pail through the openings 33 and 50. With this arrangement, it is seldom necessary to fill the pail with water, but when this is necessary water may be introduced through either of the openings 33 or 50.

It is to be understood that the form of the invention herewith shown and described is to be taken as a preferred example of the same, and that various changes in shape, size and arrangement of parts may be resorted to, without departing from the spirit of the invention or the scope of the subjoined claims.

Having thus described my invention, I claim:

1. A golf ball washer comprising an upright pail, a substantially horizontal support plate mounted within the pail near its upper end, a brush holding bracket dependingly supported by the support plate and extending near the bottom of the pail, a pair of opposed spaced upstanding brushes disposed beneath the support plate and having their lower ends pivotally secured to the brush holding bracket, the upper ends of the brushes being swingable toward and away from each other, spring means connected with the support plate and engaging the brushes near their upper ends for resiliently urging the brushes toward each other, and a golf ball holding paddle slidably mounted between the brushes for reciprocation and having an opening forming a pocket for a golf ball.

2. A golf ball washer comprising an upstanding pail, a substantially horizontal support plate arranged within the pail near the upper end thereof, a depending U-shaped bracket secured to the support plate and extending into the pail below the support plate, a pair of opposed scrubbing brushes arranged between the sides of the U-shaped bracket and having their lower ends pivotally connected to the sides, the brushes extending upwardly in substantially vertical parallel relation, depending leaf springs secured to the support plate upon opposite sides of the brushes and engaging the brushes near their upper ends to resiliently urge them together, means connected with the support plate and engaging the leaf springs to adjust their tension, and a vertically reciprocatory paddle slidably mounted between the brushes and having an opening for holding a golf ball, the upper end of the paddle extending above the support plate.

3. A golf ball washer comprising an upstanding pail, a substantially horizontal support plate mounted within the pail near its top end, a substantially U-shaped brush holder dependingly secured to the support plate and extending into the pail below the support plate, a pair of op-

posed spaced upstanding scrubbing elements arranged between the sides of the U-shaped holder and pivotally connected near their bottom ends to the holder, the upper ends of the brushes being vertically swingable toward and away from each other, resilient means connected with the scrubbing elements near their upper ends to resiliently urge them together, a vertically reciprocatory paddle arranged between the scrubbing elements and slidably mounted in the support plate and having an opening for holding a golf ball, and a stop pin secured to the paddle for engagement with the support plate when the paddle is shifted upwardly to prevent the separation of the paddle from the washer.
